CLAIM

The ornamental design for a power tool, as shown and described.

DESCRIPTION

Cross reference is made to copending U.S. utility patent application Ser. No. 14/964,838 entitled "Rotary Power Tool Lighting System" by Padgett et al., filed on even date herewith.

FIG. 1 is a perspective view of a first embodiment of a power tool showing our new design;

FIG. 2 is a left side elevational view showing the design for the power tool of FIG. 1;

FIG. 3 is a right side elevational view showing the design for the power tool of FIG. 1;

FIG. 4 is a front elevational view showing the design for the power tool of FIG. 1;

FIG. 5 is a rear elevational view showing the design for the power tool of FIG. 1;

FIG. 6 is a top plan view showing the design for the power tool of FIG. 1; and

FIG. 7 is a bottom plan view showing the design for the power tool of FIG. 1.

FIG. 8 is a perspective view of a second embodiment of a power tool showing our new design;

FIG. 9 is a left side elevational view showing the design for the power tool of FIG. 8;

FIG. 10 is a right side elevational view showing the design for the power tool of FIG. 8;

FIG. 11 is a front elevational view showing the design for the power tool of FIG. 8;

FIG. 12 is a rear elevational view showing the design for the power tool of FIG. 8;

FIG. 13 is a top plan view showing the design for the power tool of FIG. 8; and,

FIG. 14 is a bottom plan view showing the design for the power tool of FIG. 8.

The broken lines shown in the drawings illustrate portions of the power tool that form no part of the claimed design.
